UNITED STATES PATENT OFFICE

JEAN FROMONOT, OF LE PEAGE DE ROUSSILLON, FRANCE, ASSIGNOR, BY MESNE ASSIGNMENTS, TO DU PONT RAYON COMPANY, OF NEW YORK, N. Y., A CORPORATION OF DELAWARE

SKEINING

Application filed May 23, 1928, Serial No. 279,928, and in France May 24, 1927.

In the winding of threads into hanks, the name of leases is given to the diamond-shaped openings formed by the threads of the hank when the latter is spread on the reel on which it has been formed; it is through these leases that a thread is passed (tie-up or hank thread) intended to maintain the crossing of the hank during the manipulations to which it may be subjected up to the unwinding.

Great difficulties are met with in practice in obtaining hanks having well defined leases, even when every possible precaution is taken in order to avoid variations in the hygroscopic conditions during the duration of the whole operation of formation of the hanks. It is, in fact, frequently observed that the diamonds are not correctly formed; they override each other so that, in tying up, the work-girl is compelled to create with her finger the passage through the threads at the risk of damaging the thread or of performing a wrong distribution of the silk, that is, in allotting to one side of the diamond, for example, the silk which should be allotted to the other side.

This may be inconvenient at the moment of unwinding and particularly in the case when these hanks must be treated for hank-dyeing or for sizing. Moreover, it often happens that on the two external edges of the hank there exist two ridges arising from the fact that the apices of the diamonds on these external edges do not all coincide with the webs of the reel, so that these apices, being without support, follow the thread in its movement during the formation of the hank and come back towards the inside of the hank forming ridges. These threads which have in this manner a reduced tension are fallen threads.

I have ascertained that it was essential for effecting a satisfactory tying up and thereby greatly improving the conditions in which unwinding takes place, that the formation of fallen threads which occur on the external

edges of the hanks, as has been described, should be completely prevented, and also that the pattern made by the threads of the hank should be identical on all the faces of the reel, as far as concerns the number and the arrangement of the diamonds formed.

The theoretical study of the problem which I have undertaken for the purpose of obtaining hanks in the state of perfection so defined has shown that, if m is the number of diamonds along the perimeter of the bank (and therefore vertically opposite), if n is the number of diamonds contained in the width of the hank, and if l is the number of webs of the reel, then it is necessary that $m=l$; n being a whole number and m and $2n$ prime to each other, which requires m to be odd.

According to the present invention, hanks without fallen threads are obtained having leases perfectly neat, identically disposed on all the faces of the reel, by forming the hanks so that the apices of the diamonds on the external edges of the hank are in odd numbers and are all formed on the webs of the reel and on these webs only. In other words, there is in the direction of the perimeter of the hank an odd number of diamonds which is equal to the number of the webs of the reel, and on each web of the reel there is in the width of the hank a whole number of diamonds, the lateral apices of which rest upon the web.

Referring to the appended drawing:

Figures 1, 2, 3 and 4 show as examples the developments of several hanks for which different values of m and n have been chosen.

Figures 5 and 6 represent diagrammatically in front and side elevation an apparatus for the preparation of hanks by the process according to the invention.

In Figure 1 the hank has been obtained according to the present invention. The selected values are: $m=7$, $n=3$. It is seen that all the apices A^0 , A^1 , A^2 , A^3 , etc. of the diamonds on the external edges of the hank rest on the webs I, II, III of the reel and that

on each of these webs there is a whole number of diamonds (apices A⁰, A¹, A²).

In Figure 2 the hank has been again obtained in accordance with the present invention, the selected values being $m=l=5$, $n=7$. The same fact is observed. This manner of forming the hank is particularly interesting in practice, the number of tie-up threads (5) and the number of leases (7) giving a remarkable conformation of the hank.

In Figure 3, on the other hand, a hank formation is represented in which contrarily to the present invention the number m , taken equal to the number l of webs of the reel is even, $m=l=4$ (case arising frequently in former practice) and where the number of leases is 7.

It is seen on Figure 3 that there is not a whole number of diamonds in the width of the hank, and that there are on the external edges of the hank diamond apices not supported by the webs of the reel. The unsupported thread will take the direction shown dotted and will be a fallen thread.

25 It must be noticed that in Figures 1, 2 and 3 the diamonds illustrated are all of equal dimensions, which implies that the motion of the thread-guiding device, which distributes the thread on the reel, is uniform.

30 If as was generally the case hitherto the motion of this device is wavy, the dimensions of the leases decrease from the central portion of the hank towards the edges, as shown on Figure 4. It is advantageous for tying up easily that all the leases should have identical dimensions, and the attainment of this desideratum by adopting a uniform speed for the alternative motion of the thread-guiding device is a secondary feature of the present invention.

For performing the preparation of hanks according to the present invention, it is necessary for the reels to have an odd number of webs, and the ratio of the speeds of the reels (in revolutions per minute) and of the thread-guiding device (in number of double runs per minute) will be selected to be such that the conditions above indicated are fulfilled. It is easy to ascertain by calculation that if c is the number of double runs of the thread-guiding device per minute and g the speed of rotation of the wheel, in revolutions per minute, one has in the case considered in the present invention where m and $2n$ are prime to each other

$$\frac{c}{g} = \frac{m}{2n}$$

60 In Figures 5 and 6, 1 is a reel having an odd number of webs (5 for example), if it is desired to prepare hanks according to the scheme of Figure 2; 2 is the thread-guiding device, 3 is the controlling device for the latter. This arrangement comprises a helicoidal cam, so as to obtain a uniform motion. The
65

inter-dependence of the motion of the reel and of that of the thread-guiding device is obtained by means of a gear-train 4, so that the speed ratio may be given the required value for the preparation of the skeins, in accordance with the present invention.

In the case of the drawing, Figure 2, one must have

$$\frac{c}{g} = \frac{5}{14}$$

The required number of movable webs is provided on the reel, for example, two movable webs 5, 6 for a reel with five webs and these movable webs are connected to each other by any suitable means, for example, by a sleeve 7, slidable on the axle 8 of the reel and connected to the movable webs by bars 9.

I claim:

1. A process for winding hanks of textile fibres without fallen threads and having substantially perfectly defined leases disposed identically on all the faces of the reel comprising forming the hanks having an odd number of the diamond apices on the external edges of the hank. 90

2. A process of winding hanks of textile fibres without fallen threads and having substantially perfectly defined leases disposed identically on all the faces of the reel comprising forming in the direction of the perimeter of the hank an odd number of diamonds equal to the number of webs of the reel and on each web of the reel a whole number of diamonds, the lateral apices of which rest upon the web. 95 100

3. An apparatus for winding hanks of textile fibres without fallen threads and having substantially perfectly defined leases comprising a reel having an odd number of webs, a thread-guiding device, means to rotate said reel and impart motion to said thread guide so that the ratio of c , the number of double runs per minute of the thread-guiding device to g , the speed of the reel in revolution per minute, where m is the number of diamonds along the perimeter of the hank, n is the number of diamonds contained in the width of the hank, is

$$\frac{c}{a} = \frac{m}{2n}$$

4. An apparatus for winding hanks of textile fibres without fallen threads and having substantially perfectly defined leases comprising a reel having an odd number of webs, a plurality of said webs being movable, and means connecting said movable webs.

5. An apparatus for winding hanks of 125
textile fibres without fallen threads and hav-
ing substantially perfectly defined leases
comprising a reel having an odd number of
webs, a plurality of said webs being mov-
able, and means connecting said movable 130

webs, said means including a movable sleeve disposed on the axle of said reel and a rod connecting each of said movable webs to said sleeve.

5 6. An article of manufacture comprising a hank of textile fibres having an odd number of vertically opposite apices along the perimeter of the hank and being prime with the number of leases.

10 In testimony whereof, I have affixed my signature to this specification.
